UNITED STATES PATENT OFFICE.

NICK SIRBOLA, OF UNION CITY, NEW JERSEY.

WINDOW-SASH FASTENER.

Application filed August 16, 1926. Serial No. 129,538.

This invention relates to improvements in window sash fasteners.

The primary object of the invention resides in a means for locking either or both the upper and lower sashes in a partially opened position so that fresh air may be admitted to a room without fear of an unauthorized person making an entry therethrough.

Another object of the invention is the provision of a fastener bar adapted to be carried by the meeting rail of the lower sash for co-action with a pair of notched bars mounted respectively on the side rail of the upper sash and of the adjacent window frame, there being a means for fastening the fastener bar in fastening position from the inside so that the same cannot be actuated by the insertion of an instrument from the outside between meeting rails.

Another object of the invention is to provide a window sash fastener which may be installed on window sashes now in use by any one unskilled in the art of mechanics.

A still further object aims to provide a window sash fastener which is simple in construction, easy to actuate from the inside, and positive in its locking action.

With these and other objects in view, the invention resides in certain novel construction and combination and arrangement of parts, the essential features of which are hereinafter fully described, are particularly pointed out in the appended claim, and are illustrated in the accompanying drawing, in which:

Figure 1 is a perspective view of my improved sash fastener showing the same in locked position upon a window.

Figure 2 is a horizontal sectional view on the line 2—2 of Figure 1 but showing in dotted lines the position of the lock bar when in an unlocked position.

Figure 3 is a vertical sectional view on the line 3—3 of Figure 2.

Referring more particularly to the drawing, the reference numeral 10 designates the window casing in which the upper and lower sashes 11 and 12 are slidably mounted. My improved sash fastener comprises a pair of angle bars 13 and 14 respectively mounted on the window casing 10 and the inner face of one of the side rails of the upper sash 11. One of the flanges of the angle bars extends parallel to the meeting rails and is notched as at 15 and 16, the said notches being dis-

posed in horizontal alignment when the sashes are in a closed position, so as to receive the fastener bar presently to be described. The other angular flange of the angle bars fit flat against their supporting surfaces and through which fastening elements in the nature of screws 17 pass for supporting the bars thereon. The bars are relatively short compared to the height of an ordinary window, for it is only practical to fasten the sashes in a partially opened position, for if the sashes were fastened in full open position, then an unauthorized person could enter through the window and the purpose of this invention would be defeated.

Mounted on the meeting rail of the lower sash 12 is a latch means 18 which includes an attaching or base plate 19, fastened to the meeting rail by screws or the like 20. An arm or tongue 21 is bent from the base plate and over the body of the same for co-action with the plate to serve as a bearing for a pivot pin 22, which pin passes through a fastener bar 23 approximately midway between its ends for pivotally mounting the same upon the plate. The fastener bar is of such length as to cause both ends of the same to lie within two horizontally aligned notches 15 and 16 of the bars 13 and 14 respectively, and yet clear the walls of the notches when the bar is swung in one direction to lie within the confines of the sides of the meeting rail of the lower sash, for allowing free sliding movement of the sash when being moved from open to closed position or vice versa.

One of the ends of the fastener bar is provided with an opening 24 for receiving a removable key 25 carried by one end of a string or chain 26, and which chain has its other end connected with the window casing or any suitable support. It will be appreciated that the walls of one of the sets of notches prevents further movement of the fastener bar when seated therein, while the key when in position in the opening 24 serves to prevent movement of the fastener bar in an opposite direction, thus preventing an unauthorized person from inserting an instrument between the meeting rails from the outside of the window with an effect of moving the fastener bar from a locked to an unlocked position.

While I have described what I deem to be the most desirable embodiment of my invention, it is obvious that many of the de-

tails may be varied without in any way departing from the spirit of my invention, and I therefore do not limit myself to the exact details of construction herein set forth nor to anything less than the whole of my invention limited only by the appended claim.

What is claimed as new is:—

A window sash fastener comprising a pair of angle bars having one of their flanges notched, said angle bars adapted to be respectively mounted upon the upper sash of a window and the casing thereof, and a latch

device including an attaching plate, and an elongated bar pivotally mounted thereon, the ends of said bar adapted to respectively seat within the aligned notches of said angular bars when said bar is moved to a locking position, one end of said bar having an opening therein, and a key insertible in said opening to fasten said bar in locking position. 15 20

In testimony whereof I have affixed my signature.

NICK SIRBOLA.
